Stockbridge & Boott.

UNITED STATES PATENT OFFICE.

GEORGE G. BROWN, JR., OF ANN ARBOR, MICHIGAN.

CARBURETOR.

Application filed April 22, 1922. Serial No. 555,974.

To all whom it may concern:

Be it known that I, GEORGE G. BROWN, Jr., a citizen of the United States, residing at Ann Arbor, in the county of Washtenaw and 5 State of Michigan, have invented certain new and useful Improvements in Carburetors, of which the following is a full, clear, and exact description.

In the operation of explosion engines, it 0 is a commonly accepted fact that maximum economy can be obtained only by burning dilute or lean mixtures that are heated, and that maximum power can be obtained only by comparatively concentrated or rich mixtures supplied to the engine comparatively cold. If cold air is admitted to the carburetor, it is necessary that more fuel be added in order to have a sufficiently concentrated mixture, owing to the fact that 5 the density of the air increases with a decrease of temperature. As the temperature of the mixture decreases, the mixture should be richer in order to maintain the velocity of reaction of the burning gases at a rate which insures an application of the explosive energy within the desired period in the cycle of movement of the piston. With the common type of carburetor, an operator, by using a dash adjustment, can regulate the mixture to make it as dilute or lean as temperature and load conditions permit, and thus obtain greater mileage than if he were not able to so control the mixture. The average driver, however, is not skilled in the adjustment of the carburetor to the best advantage, and therefore, is unable to use such an adjustment effectively and economically.

An object of the invention is to provide an improved carburetor for normally providing a lean, economical mixture, and adapted to provide a rich, powerful mixture when necessary or desired; with which a single manually controlled member by the extent of its movement, controls the character of the mixture under all operating conditions; which may be advantageously combined with mechanism for automatically varying the proportions of the components of the mixture with variations in temperature and load; and which is efficient, simple, compact and relatively inexpensive. Other

objects and advantages will be apparent from the following description of an embodiment of the invention and the novel features will be particularly pointed out in claims. 55

In the accompanying drawing:

Fig. 1 is an elevation of a carburetor constructed in accordance with this invention;

Fig. 2 is a sectional elevation of the same;

Fig. 3 is another sectional elevation of 60 the same; and

Fig. 4 is a sectional plan through the lower part of the carburetor.

The invention, is illustrated and described as applied to a carburetor of the type disclosed in U. S. patent to Breath No. 1,153,891, and also as having a thermostatic control of the fuel supply as disclosed in my co-pending application Serial No. 473,249, filed May 28th, 1921. The fuel is received in the 65 float chamber 1 through fuel supply pipe 2 leading from a suitable storage tank, not shown. The fuel in this float chamber is maintained at a fixed level by suitable, well-known float-controlled mechanism. A conduit (not shown), leads from the float chamber 1 to a passage 3 extending vertically along the casing 4 of the mixing chamber 5. A throttle drum or cylinder 6, is rotatively mounted in the mixing chamber between a wall of the casing 4 and a removable 75 circular wall 7 of the casing. The wall 7 is held rotatively against the casing 4 by a clamping ring 8 which has a flange overlying the periphery of the wall 7 and is secured to the casing in a suitable manner, such as by screws 9 passing through the same and into the casing. When the screws 9 are tightened to force the clamping ring 8 against the face of the casing 4, the wall 80 7 will be frictionally held against rotation relatively to the casing.

The passage 3 at its upper end is provided with spaced ports 10 and 11 both of which open into a conically shaped recess 12 in the 85 casing in which is rotatably mounted a tubular valve element 13 with a tapered nose fitting in the conical recess and overlying the port 10. The tapered nose of the valve element 13 is provided with a port 14 which 100 is adapted during the rotation of the valve element to cooperate with the port 10 and

vary the flow of fuel through the passage 3 into the interior of the tubular valve element. A sleeve 15 is rotatably mounted in an axially disposed aperture 16 of the rotatable side wall 7 of the casing. An arm 17 is provided with an aperture through which the sleeve 15 passes, and the arm is held against axial movement thereon between the wall 7 and a flange 18 at the inner end of the sleeve. The arm is keyed or otherwise secured to the sleeve 15 for rotation therewith and its ends are disposed in slots 19 in the drum 6 so as to cause rotation of the drum 6 with the sleeve 15. The valve element 13 extends axially into the sleeve 15 and rotates relatively thereto.

An extension 20 is telescopically received within the valve element 13 and by means of a pin 21, extending diametrically through the extension and cooperating with longitudinally extending slots 22 in the valve element, causes a rotation of the valve element with the extension and permits a limited axial movement of the extension relatively to the valve element. The extension is reduced at its outer end and passes through a reduced bore in the sleeve to limit movement of the extension relatively to the sleeve. A throttle arm 23 is keyed or otherwise fixed upon the reduced outwardly projecting end of the sleeve 15 so as to rotate therewith. An arm 24 is keyed or otherwise fixed upon the extension 20 of the valve element so as to rotate therewith and the arm 24 may be held against axial movement thereon in a suitable manner, such as by a nut 25 threaded upon the reduced projecting end of the extension 20. A headed screw 26 passes through an aperture in the arm 24 and has threaded engagement with an arm 27 formed integrally with the throttle arm 23. A nut 28 is disposed upon the screw 26 between the arm 27 and the arm 24, and a spring 29 acts between the screw 28 and the arm 24 in a direction to normally cause the separation thereof and press the arm 24 against the knurled head of the screw 26. When the screw 26 is rotated, the arm 24 will be adjusted toward or from the arm 27 dependent upon the direction of rotation of the screw. The nut 28 is used to control the pressure of the spring 29 against the arm 24 so that the adjustment may be made accurately and conveniently by simply turning the screw 26. When the adjustment is once properly made the nut 25 serves as a lock nut compressing arm 24 against arm 27 and sleeve 15 thereby preventing any change in the adjustment between arms 24 and 27. When the throttle arm 23 is given a partial rotation through a suitable connection to its upper end, it will cause a corresponding rotation of the sleeve 15, the throttle cylinder 6, and the valve element 13.

The throttle cylinder 6 is provided with

a mixture outlet port 30 and an air intake port 31 at diametrically opposite points. The port 30 controls the passage of the mixture from the mixing chamber within the casing 4 into the conduit 32 through which it passes to the intake manifold. The port 31 of the cylinder controls the passage from the conduit 33 into the mixing chamber. The valve element 13 is provided in its interior with a restricted axially disposed aperture 34 in which a frustro-conical governor element 35 is disposed for reciprocation endwise through the same. A head 36 upon the small end of the governor element limits the movement of the governor element in one direction through the restricted opening 34 and the other or larger end restricts the movement of the governor element in the opposite direction. A bearing block 37 is mounted for sliding movement within the valve element endwise thereof, and a spring 38 within the valve element acts between the bearing block and the head 36 of the governor element to normally press the governor element to the right (Fig. 2) and carry the smallest portion thereof into the opening 34. The effective passage through the opening 34 is then a maximum.

A bimetal thermostat 39 is anchored at one end to the valve element, loops downwardly through a slot 40 in the element, doubles back within the element, and bears upon the end of the bearing block 37. With changes in temperature, the thermostat will either shift the block 37 in a direction to compress the spring 38, or in an opposite direction to partially release the spring 38. A spring 41 is compressed between the anchored end of the thermostat and the extension of the valve element for normally pressing the nose of the valve element into the conical recess. An aperture 42 is provided in the wall of the conduit 33 which is normally closed by a flap valve 43. This flap valve comprises a plate carried by an arm 44 that is pivoted intermediate of its ends upon a pin 45 passing through the wall of the intake conduit. The free end of the arm 44 extends into the port 31 so as to be engaged and operated by an edge of the port when the throttle cylinder has been rotated in a direction to completely open the intake port 31 to the maximum extent. This operation of the flap valve uncovers the opening 42 in the intake conduit.

An auxiliary frustro-conical valve element 46 is rotatively mounted in the apex portion of the conical recess 12 and extends through the adjacent wall of the casing and is provided with an operating arm 47. The auxiliary element 46 is recessed at its base and is provided with a port 48 leading from the recess to its outer surface which is adapted to cooperate with the port 11 of the fuel passage 3. The adjacent end of the valve

element 13 is apertured as at 13^a so that when the ports 48 and 11 are in alignment liquid fuel may pass through the same into the recessed end of the element 46 and thence 5 through the aperture 13^a in the end of the valve element into the interior thereof. The auxiliary element 46 is used to admit fuel therethrough when starting the engine, at which time a rich mixture is desired. The 10 rotatable side wall 7 of the casing is provided with a lug 49 which carries an adjustable screw 50 forming a stop for the throttle arm 23. The lug 47 is adjustable with the wall 7 when the ring 8 is loosened and the 15 wall is rotated. When the wall 7 is clamped to the casing the rotation of the screw 50 provides a finer adjustment in determining the effective stopping position. The exposed portion of the valve element 13 within the 20 mixing chamber is provided with apertures 51 through which the fuel passes from the interior of the valve element into the mixing chamber within the throttle drum. The conduit 33 is connected to a hot air stove (not 25 shown), which is heated in a suitable manner such as by the exhaust gases, so that the air normally entering the mixing chamber through the conduit 33 has been heated.

In the operation of the carburetor, in 30 starting the engine, the arm 47 of the priming device is rotated to bring the port 48 of the auxiliary valve element 46 into alignment with the port 11. The suction in the intake manifold will be communicated 35 to the conduit 32 and thus to the mixing chamber. The hot air entering the intake conduit 33 passes through the port 31 of the throttle cylinder into the mixing chamber, and concomitantly the fuel is drawn by 40 suction from the passage 3 through the ports 11 and 48 into the interior of the valve element and thence through the apertures 51 into the moving column of heated air. Fuel also passes through the ports 10 and 14 into 45 the interior of the valve element. The fuel is vaporized by the heated air and carried along into the intake manifold. When the engine has been started, the arm 47 is rotated to carry the port 48 out of alignment 50 with the port 11 and the fuel is drawn into the mixing chamber solely through the co-operating ports 10 and 14.

The suction communicated from the intake manifold to the mixing chamber causes 55 a movement of the governor element 35 to the left (Figure 2), so as to draw the larger portion of the governor element into the aperture 34 and restrict the effective passage through the valve element to the apertures 60 51 and thus control the amount of fuel added to the mixing chamber. This operation of the governor is clearly set forth in the Breath patent hereinbefore referred to and per se forms no part of the present invention.

The thermostat 39 is responsive to variations in the temperature of the incoming air and by its movements varies the stress of the spring 38 upon the governor element. The greater the stress by the spring 38 upon the governor element, the less the movement of the governor element by suction in the mixing chamber, and accordingly the less restriction to the flow of the fuel through the valve element. This thermostatic control per se forms the subject matter of the separate application hereinbefore referred to.

During the operation of the engine, the throttle arm 23 is manipulated to rotate the 80 throttle cylinder and vary the effective intake aperture or port 31 in a manner well known. At the same time the valve element 13 will be rotated to shift the port 14 with respect to the fixed port 10 of the fuel passage so as to vary the fuel admitted to the mixing chamber in proportion to the amount of air admitted to the mixing chamber. The adjustment by the screw 26 can be made so as to provide a mixture which is lean and economical for the ordinary or normal range of the carburetor, which mixture is varied slightly by the governor and thermostat. When, however, the throttle moves into wide 90 open position, the port 31 will be open to its fullest aperture, although not yet in alignment with the intake conduit 33 at its left side, and the maximum amount of hot air may enter the mixing chamber and the proportional amount of fuel will be admitted 100 through the valve element 13. The engine will then be developing the maximum power which is possible with maximum efficiency.

If additional power is desired, the throttle arm 23 is given a slight additional movement in the opening direction which causes an edge of the port 31 to engage the projecting end of the arm 44 of the flap valve and rotate the arm to carry the flap valve 43 away from the intake conduit 33 and uncover the aperture 42. Cold air will, therefore, be admitted directly into the intake conduit and thence into the mixing chamber. This cold air is of greater density than the hot air and therefore should have a greater proportion of fuel. Also to obtain maximum power a greater proportion of fuel should be admitted so as to have a richer mixture. During this slight additional movement of the throttle arm the valve element 13 will be also given a slight additional movement in an opening direction so as to uncover a greater portion of the port 10 and thereby admit additional fuel through the valve element to the mixing chamber.

The size and shape of the ports 10 and 14 may be readily designed to provide the necessary change in the proportion of fuel and air during this slight movement of the valve element. The denser air and richer mix-

ture gives the engine greater power during this extreme position of the throttle. When the demand for maximum power ends, a slight return movement of the throttle arm 5 will release the valve 43 which then, operated by gravity, suction or a spring not shown, returns to the closed position and shuts off the cold air. As the excess fuel is also shut off by the same return movement of the 10 throttle arm, the engine at once returns to its most economical operating condition. It will therefore be seen that with a single throttle arm the carburetor throughout its normal range supplies the most economical 15 and efficient mixture to the engine, and when maximum power and speed are desired, a slight further movement of the throttle arm will cause the admission of a rich, cool and therefore powerful mixture to the engine. 20 This additional movement which is in the same direction as that usually given to the throttle when greater power is desired, is not confusing to the motorist, or difficult to remember. The single throttle member 25 operated in the usual manner and controlling all operations of the engine thereby eliminates the necessity of using dash adjustments of the carburetor or various other adjustments which may be provided for use 30 under varying operating conditions. In addition, the thermostatic control of the fuel supply automatically changes the mixture proportions, with changing temperature and the governor element changes the mixture 35 proportions with changing load so that the carburetor is completely automatic in action except as the throttle member may be operated to increase the speed or power of the engine. This single and automatic control 40 is very important since the carburetor provides maximum efficiency for engines operated by unskilled motorists and never needs adjustment after it has once been properly set. 45 It will be obvious that various changes in the details and arrangements of parts herein described and illustrated for the purpose of explaining the nature of the invention, may be made by those skilled in the art within 50 the principle and scope of the invention.

I claim:

1. In a carburetor, a mixing chamber, means for supplying liquid fuel to said chamber, a conduit for supplying hot air to said chamber, a valve controlling the admission of fuel to the chamber, a valve controlling the quantity of air passing through said chamber, a common operating device for operating said valves concomitantly to 55 vary the fuel supply with variations in the quantity of air admitted, and means operable through the common operating device adapted to admit cold air to the chamber after the air valve has been approximately completely opened and the common operat-

ing device has been given a further movement to admit more fuel to the chamber.

2. In a carburetor, a mixing chamber, means for supplying liquid fuel to said chamber, a conduit for supplying hot air 70 to said chamber, a valve controlling the admission of fuel to the chamber, a valve controlling the quantity of air passing through said chamber, a common operating device for operating said valves concomitantly to 75 vary the fuel supply with variations in the quantity of air admitted, and a valve in said hot air conduit operable through the common operating device adapted to admit cold air to the chamber after the air valve 80 has been approximately completely opened and the common operating device has been given a further movement to admit more fuel to the chamber.

3. In a carburetor, a hot air intake conduit, a throttle device controlling said conduit, means controlled by the throttle device for admitting fuel to the intake conduit according to a predetermined ratio to provide a lean hot mixture, and means for 90 admitting cold air to the intake conduit anterior to the admission of the fuel thereto, at approximately wide open position of the throttle device.

4. In a carburetor having a hot air intake 95 conduit, a throttle device controlling said conduit, means for supplying fuel to the intake conduit, a valve in the intake conduit anterior to the fuel admission point, normally closed when the throttle device is in 100 all positions less than approximately wide open, and operable by the throttle device to admit cold air directly to the intake conduit automatically when the throttle device has been opened wide.

5. In a carburetor, a casing, a hot air supply conduit leading thereto, a throttle cylinder in said casing having a part controlling the admission of hot air from the conduit to the casing, a fuel supply device for supplying fuel to the casing, a valve controlling the admission of fuel to the casing, means for adjustably coupling the throttle cylinder and fuel supply valve for supplying fuel and hot air to the casing in a determined and variable proportion, a valve in 110 said conduit for admitting cold air thereto, said valve being operable by the throttle cylinder when the cylinder is given a further movement after having reached approximately wide open position, whereby cold air will be admitted to the casing with a further operation of the fuel supply valve.

6. In a carburetor, a casing, a hot air supply conduit leading thereto, a throttle cylinder in said casing having a part controlling the admission of hot air from the conduit to the casing, a fuel supply device for supplying fuel to the casing, a valve controlling the admission of fuel to the cas- 120 125 130

ing, means for adjustably coupling the throttle cylinder and fuel supply valve for supplying fuel and hot air to the casing in a determined and variable proportion, a valve in said conduit for admitting cold air thereto, said cold air valve having an arm projecting into the path of the throttle cylinder to be automatically operated thereby

when the cylinder is given a further movement after having reached approximately 10 wide open position, whereby cold air will be then admitted to the casing with a further operation of the fuel supply valve.

In witness whereof, I hereunto subscribe my signature.

GEORGE G. BROWN, JR.
